United States Patent

Des. 241,846

Patented Oct. 12, 1976

241,846

LAVATORY

Robert Ribits and Russell Blanchard, Marshall, Mich.,
assignors to Leigh Products, Inc.

Filed Jan. 13, 1975, Ser. No. 540,719

Term of patent 14 years

Int. Cl. D23—02

U.S. Cl. D23—58

Fig. 3

Fig. 4

FIG. 1 is a top plan view of a lavatory showing our new design.

FIG. 2 is a cross-sectional view thereof taken on line 2—2 of FIG. 1.

FIG. 3 is a side elevational view thereof.

FIG. 4 is a rear elevational view thereof.

We claim:

The ornamental design for a lavatory, as shown.
